(57) **CLAIM**

The original design for an electric scooter, as shown and described.

(30) **Foreign Application Priority Data**

DESCRIPTION

Apr. 7, 2011 (WO) 596 896 301

FIG. 1 is a front, right side perspective view of the electric scooter of the present invention;

(51) **LOC (9) Cl.** **12-11**

FIG. 2 is a front, left side perspective view thereof;

(52) **U.S. Cl.** **D12/110**

FIG. 3 is a rear, right side perspective view thereof;

(58) **Field of Classification Search** D12/110,

FIG. 4 is a rear, left side perspective view thereof;

D12/111; D21/423; 180/219, 220, 221;

FIG. 5 is a right side view thereof;

280/288.1-288.3

FIG. 6 is a left side view thereof;

See application file for complete search history.

FIG. 7 is a front view thereof;

(56) **References Cited**

FIG. 8 is a rear view thereof;
